UNITED STATES PATENT OFFICE.

OVIDE LAMOTHE AND GEORGE LAMOTHE, OF MONTREAL, QUEBEC, CANADA.

SANITARY TOOTHPICK-HOLDER.

1,204,364.

Specification of Letters Patent.

Patented Nov. 7, 1916.

Application filed June 11, 1915. Serial No. 33,607.

To all whom it may concern:

Be it known that we, OVIDE LAMOTHE and GEORGE LAMOTHE, both subjects of the King of Great Britain, and residents in the 5 city of Montreal, in the Province of Quebec, Canada, have invented certain new and useful Improvements in Sanitary Toothpick-Holders; and we do hereby declare that the following is a full, clear, and exact description 10 of the same.

The invention relates to improvements in "sanitary tooth-pick holders" and the object is to devise a holder in which the tooth-picks will be taken out automatically one 15 at a time therefore preserving them from being soiled or handled uncarefully, as they are when in an ordinary holder.

The invention consists in a receptacle and a cover therefor, of a slot in one of its sides, 20 a deflecting plate extending through said slot in the side of the casing, of a rocker having an inward dent projecting just above said deflecting plate, a handle to rock said rocker and a spring to hold back said rocker 25 in its primary position.

In the drawings, Figure 1 is a perspective view of the holder. Fig. 2 is a cross sectional view through the holder.

Like numerals of reference indicate corresponding parts in each figure.

Referring to the drawings, 1 is the casing or holder, preferably consisting of a metal box having the swinging cover 2, pivoted at 3.

3^a is a transverse slot in one side of the casing 1 and 4 is a perpendicular slot intermediate of the length and downwardly extending from said slot 3^a.

5 is a deflecting plate or slide within the 40 sides of the casing 1 outwardly projecting through the transverse slot 3^a and having the upturned end 6 and the cut out corner 7. The said plate 5 is supported by the braces 8, and 9 is a slot intermediate of its 45 width; and near the upturned end 6.

10 is a plate to which is secured the lower end of the supporting braces 8 and 11 are brackets projecting from said plate 10 and secured thereto.

50 12 is a rocker having at its lower side, the projecting portion 13 pivotally secured to

the brackets 11, and at its upper side the inward dent 14 slightly projecting through the slot 9 and 15 is the operating handle projecting through the perpendicular slot 4. 55

16 is a spring secured at one end to the plate 10 and at the other end to the rocker 12.

In the operation of the invention, the casing or receptacle 1 must first be filled with tooth-picks, placed parallel to the transverse 60 slot 3^a. The handle 15 is then pressed downwardly. The action of pressing the rocker handle pulls one of the tooth-picks by means of the dent 14 on the rocker 12. The tooth-pick slides on the outwardly projecting end 65 of the deflecting plate 5, a portion of the tooth-pick resting against the upturned end 6, the other end projecting over the cut out portion 7 of the plate 5, in order that it may be removed easily.

The form of tooth-pick holder disclosed in the drawings may be altered without departing from the scope of the claims for novelty following.

What we claim is:—

In a sanitary tooth-pick holder, in combination, a casing having a cover, a transverse slot in one side of said casing in the lower part thereof, a perpendicular slot intermediate of the length and downwardly extending from said transverse slot, a deflecting plate within said casing projecting outwardly through the said transverse slot and upturned so as to form a receiving plate, a portion of said plate being cut out, means 80 to support said deflecting plate, a slot in said plate, a rocker pivotally mounted at one end in suitable bearings in the casing and a dent in its upper part, said upper portion of the rocker slightly projecting 85 through said slot in the deflecting plate, a spring secured to said rocker at one end, the other end being rigid to the casing and a handle or arm projecting from said rocker to operate same. 90

Signed at Montreal, Quebec, Canada, this 16th day of March, 1915

OVIDE LAMOTHE.
GEORGE LAMOTHE.
